UNITED STATES PATENT OFFICE.

GEORGE S. WEBBER, OF CHICAGO, ILLINOIS.

DESIGN FOR A POLE-HOLDER.

SPECIFICATION forming part of **Design No. 26,770**, dated **March 16, 1897**.

Application filed February 1, 1897. Serial No. 621,566. Term of patent 3½ years.

To all whom it may concern:

Be it known that I, GEORGE S. WEBBER, a citizen of the United States, residing at Chicago, in the county of Cook and State of Illinois, have invented and produced a new and original Design for Exercising-Pole Holders, of which the following is a specification, reference being had to the accompanying drawings, showing a part thereof.

10 Figure 1 is a perspective view of an exercising-pole holder, showing my design. Fig. 2 is a front elevation, and Fig. 3 a side elevation of same as the holder appears detached from the position it usually occupies.

15 The principal features of my design consist of a flat base A, from which projects from the front thereof a U-shaped ledge B. The base

A is of an elongated form, as shown, with marginal scallops forming the upper and lower substantially semicircular ends, and the top 20 ends of the bifurcations of the U-shaped ledge have the upper outer corners D and E of a substantially rounded contour, as shown.

I claim—

The design for an exercising-pole holder, 25 substantially as hereinbefore shown and described.

In testimony that I claim the foregoing I have hereunto set my hand, this 22d day of October, 1896, in the presence of witnesses.

GEORGE S. WEBBER.

Witnesses:

OSCAR SNELL,
H. L. BROWN.
